UNITED STATES PATENT OFFICE.

WILLIAM H. GASKILL, OF PHILADELPHIA, PENNSYLVANIA, ASSIGNOR TO
SAMUEL W. EVANS, JR., OF PHILADELPHIA, PENNSYLVANIA.

UMBRELLA-RUNNER.

SPECIFICATION forming part of Letters Patent No. 707,838, dated August 26, 1902.

Application filed November 16, 1900. Serial No. 36,673. (No model.)

To all whom it may concern:

Be it known that I, WILLIAM H. GASKILL, a citizen of the United States, residing in the city and county of Philadelphia, State of Pennsylvania, have invented a new and useful Improvement in Spring-Cases and Runners for Self-Opening Umbrellas, of which the following is a specification.

Heretofore in the construction of a spring-case for a self-opening umbrella it has been the custom to employ solder or similar material to effect the union of the tubular portion of the spring-case with the body portion of the slotted ring attached thereto; but this method of construction is open to serious defects in practice, for the reason that the serrations or slits in said ring must be cut therein before the tubular portion is secured thereto, and in the act of soldering a portion of the solder in practice leaks through the joint between said tubular portion and ring and fills the slits in the latter, which must be afterward cleaned out, thereby entailing considerable expense in the manufacture of spring-cases for umbrellas of this character in large quantities. By my present invention I have found that by forming an annular groove in the body of the ring below the slits therein and then assembling said ring and tubular portion or barrel so that the end portion of the latter is slipped over said groove and slightly beyond the latter, after which the metal of said tubular portion is depressed into said groove by knurling, rolling, or other suitable means, a joint of a superior character can be effected without the use of solder and without necessitating the subsequent cleaning out of the slits of said ring.

To the above ends one part of my invention consists of the novel construction of a spring-case or spring-retainer for a self-opening umbrella, said spring case or retainer being composed of two parts, one being the tubular portion and the other the ring, the latter having an annular groove or recess in its body portion, into which the metal of said tubular portion is deflected or sunk by means of knurling, rolling, or other suitable means.

The other feature of my invention consists of an improved construction of a runner for a self-opening umbrella, the same having an

enlarged upper portion within which the spring interposed between the spring-case and the runner proper is contained, said runner telescopically receiving the spring-case and being provided with novel means on its upper portion, so that the metal of the upper portion of the runner-body is prevented from being forced inwardly when the stretchers are wired in position with respect to said runner, this latter provision being effected either by means of a separate ring, which is placed in position near the upper extremity of the runner, or, if desired, the upper extremity of said runner can be formed with a strengthening bead or ridge, which is rolled, knurled, or otherwise formed for the purpose specified.

It further consists of novel details of construction, all as will be hereinafter fully set forth, and particularly pointed out in the claims.

Figure 1 represents a side elevation of a spring case or retainer for a self-opening umbrella embodying my invention. Fig. 2 represents a longitudinal sectional view of Fig. 1, the section being taken on line *xx* of said figure. Fig. 3 represents a side elevation of the tubular portion of a spring case or retainer for a self-opening umbrella detached from its ring, showing the position of the parts prior to assembling. Fig. 4 represents a longitudinal sectional view of another form of spring-retainer wherein the lower portion of the body thereof is drawn down to substantially the diameter of the umbrella rod or stick. Fig. 5 represents a perspective sectional view of the spring case or retainer and its coacting spring and runner. Fig. 6 represents a vertical sectional view of my novel umbrella-runner and ring in the first stage of its manufacture. Fig. 7 represents a longitudinal sectional view of the runner and attached ring completed. Fig. 8 represents a longitudinal sectional view of another form of umbrella-runner and attached ring embodying my invention. Fig. 9 represents a longitudinal sectional view of another embodiment of my invention. Fig. 10 represents a perspective view of the ring seen in Fig. 9 in detached position. Fig. 11 represents a longitudinal sectional view of another embodiment of my invention in its first stages

of manufacture. Fig. 12 represents a longitudinal sectional view of the runner seen in Fig. 11 completed. Fig. 13 represents a side elevation of a self-opening umbrella equipped 5 with a spring case or retainer and a runner embodying my invention.

Similar letters of reference indicate corresponding parts in the figures.

Referring to the drawings, A designates a 10 spring case or retainer for a self-opening umbrella, the same consisting of the tubular portion B and the notched ring C, the latter being provided with a suitable body portion or collar D, which has formed therein the annular groove E, it being noted that the upper and lower bearings F and G are provided on either side of said groove, so as to afford a bearing for the contiguous part H of the tubular portion B. It will now be noticed that 15 said ring and collar are secured to an internal tube B' and that the latter is fitted within the tubular portion or exterior tube B.

The parts are assembled by slipping the end 20 part or extremity H of the tubular portion B over the body portion D of the ring until the extremity H occupies substantially the position seen in Figs. 1 and 2, after which the metal of the tube is sunk into the annular groove or recess E by means of knurling, 25 rolling, or other suitable means, whereby a tight joint is produced without the use of solder and the annular groove J in the outer peripheral portion of the tube is formed, which gives the finished appearance to the 30 device.

While I have described my invention as being especially applicable to spring-cases for self-opening umbrellas, it will of course be understood that the completed spring case 40 or retainer can be used for other purposes and that other changes in the manner of manufacturing the same can be made without departing from the spirit of my invention.

In Fig. 4 I have shown the body K of the 45 spring case or retainer as drawn down to nearly the diameter of the umbrella-rod L, it being apparent that the spring which in Figs. 1, 2, and 3 is contained within the tubular portion B is in the case of Fig. 4 retained in position on the exterior of said tubular portion K and abuts against the wall or shoulder M, which latter has the upwardly-extending portion N knurled, rolled, or otherwise secured in position in the same manner and for the 55 same purpose as has been described with respect to Figs. 1, 2, and 3. In this case the inner tube B', which carries the ring and grooved collar, rests against the upper side of the shoulder M.

Referring to Fig. 13, which shows the parts in assembled position, it will be apparent that as the spring case or retainer A telescopes 60 into the runner P, which latter contains the lower extremity of the spring Q, it being essential that the spring case or retainer slides or telescopes freely within said runner. I have, however, found in practice that when

the extremities R of the stretchers S are wired in position in the upper part of the runner in the act of wiring there is a tendency to 70 compress or distort the upper extremity of the runner, and the second part of my invention has special reference to providing means whereby the liability of crushing or distorting the upper extremity of the runner is prevented. In carrying out this embodiment of my invention I first sink or knurl a groove T in the laterally-extending flange U of the ring V, the parts now appearing as seen in Fig. 6, after which by suitable means the 75 outer peripheral portion of the flange U is deflected downwardly, so as to form an annular lip W, as seen in Fig. 7, the ring being afterward provided with the slits X for the reception of the ends R of the stretchers, the latter being secured in position by means of the wire lying in the annular recess Y, as is evident. It will be apparent that by the provision of the annular bead or knurl T in the position specified the upper extremity of the 80 runner-ring is greatly strengthened and the 85 liability of crushing the same during the wiring of the stretchers in position is entirely obviated.

In the construction seen in the upper portion of Fig. 8 I have shown another form of the embodiment of my invention, the metal being swelled out, as indicated at W', and the upper portion of the ring having the 90 downwardly-deflected lip or flange X', it being apparent that the swelled-out portion W' has the same function as the inner wall 95 of the recess Y, already described.

In Fig. 9 I have shown the runner-ring as provided with the laterally-extended flange 100 Y' and the exterior downwardly-deflected lip or flange Z, the upper portion of the runner-ring being embraced by the auxiliary ring A', Fig. 10, the position of the parts when assembled being clearly understood from said 105 Fig. 9.

In Fig. 11 I show the first step of another embodiment of my invention, wherein I roll or otherwise form the knurl B' in the upper portion of the runner-ring, after which the 115 flange C' is deflected so as to form the outer peripheral lip D', the function of the knurl B' being to strengthen the upper portion of the runner, as has already been explained.

In Figs. 5 and 13 I have shown the parts 120 in assembled position, and I desire to also call attention to the fact that I make the enlarged portion E' of the runner and the reduced portion F' integral, or in one piece, whereby it will be seen that the runner consists of merely the ring V and the tubular portions E' F', which latter are integral, or in one piece, whereby the cost of production is reduced to a minimum.

I make no claim herein to the feature of a 130 self-opening umbrella, as the present invention is more especially designed to protect the novel manner of securing the tubular portion of the spring-case to the slotted ring

without the use of solder in addition to the provision, broadly, of novel means to prevent the upper portion of the runner-ring from being crushed or otherwise inwardly distorted during the wiring of the stretchers in position upon the telescoping tubular portion B of the spring case or retainer.

Having thus described my invention, what I claim as new, and desire to secure by Letters 10 Patent, is—

1. In a spring-case for an umbrella, a tube, and a ring having a collar, the latter being provided with an annular groove on the exterior thereof, the contiguous metal of said 15 tube being deflected into said groove and secured to the wall thereof.

2. In a spring-case for an umbrella, an exterior tube, a ring having a collar, said collar being provided with an annular groove on 20 the exterior thereof, the contiguous metal of the exterior tube being deflected into said groove and engaging with the surface of said collar on opposite sides of said groove.

3. In a spring-case for an umbrella, a ring 25 having a collar, a groove on the exterior of said collar, and an exterior tube having its upper extremity knurled or otherwise deflected into said groove, the lower portion of said exterior tube being of reduced diameter.

30 4. A runner for a self-opening umbrella, consisting of a body portion having a ring at-

tached thereto, said ring having an outer downwardly-deflected peripheral lip or flange, and an inner annular strengthening device between said lip and the inner wall of said 35 ring whereby the upper portion of said ring is prevented from being crushed inwardly in the act of wiring the stretchers in position.

5. As an improved article of manufacture, a runner having an annular groove at its upper portion, said groove being closed at its top and open at its bottom, and annularly-disposed strengthening means on the inner wall of said groove between the inner and outer walls of the ring, whereby the upper 45 portion of the device is prevented from being crushed inwardly during the wiring of the stretchers in position.

6. A spring-case for an umbrella consisting of an interior tube, a notched ring having a 50 collar, said ring and collar being carried by said tube, said collar being provided with an annular groove on the exterior thereof, and an exterior tube, the metal of which latter is deflected into said groove and engaged 55 with the portion of said collar on the opposite sides of said groove.
